UNITED STATES PATENT OFFICE.

HAAKON PETERSON, OF COEUR D'ALENE, IDAHO.

DESIGN FOR A FRAME FOR PICTURES, MIRRORS, AND THE LIKE.

60,499.

Specification for Design. Patented Feb. 28, 1922.

Application filed April 14, 1921. Serial No. 461,424. Term of patent 14 years.

To all whom it may concern:

Be it known that I, HAAKON PETERSON, a citizen of Norway, residing at Coeur d'Alene, in the county of Kootenai and the State of Idaho, have invented a new, original, and ornamental Design for Frames for Pictures, Mirrors, and the like, of which the following is a specification, reference being had to the accompanying drawing, forming a part thereof.

Figure 1 is a front elevation of the frame, and

Fig. 2 is a side elevation of the frame shown in Fig. 1.

What is claimed is:—

The ornamental design for a frame for pictures, mirrors, and the like, as shown.

HAAKON PETERSON.
